COUPLED COIL SYSTEM

Ewoud Adriaan van Yzeren, Eindhoven, Netherlands, assignor, by mesne assignments, to Radio Corporation of America, New York, N. Y., a corporation of Delaware

Application October 4, 1938, Serial No. 233,181
In Germany February 10, 1938

3 Claims. (Cl. 178—44)

This invention relates to a coupled coil system comprising at least one fixed and one movable coil more particularly for high-frequency band-pass filters in which the inductive coupling of the coils 5 is adjustable by varying the relative position of the coils and the adjustment of the coupling does not alter substantially the self induction of the coils.

A known coil system satisfying this condition 10 comprises two disc-shaped coils which are arranged so that the axis of the stationary coil perpendicularly intersects the axis of the movable coil substantially in the coil centre of the last mentioned coil, the movable coil being movable in 15 the direction of its axis.

An important advantage of the well-known arrangement is that the two coils can be coupled very loosely or, if desired, can be completely decoupled. However, it has been found that the 20 well-known arrangement does not permit a compact construction. Indeed, if the coils are closely approached together the displacement required for modifying the coupling factor by a definite amount is so slight that the adjustment of the 25 movable coil involves difficulties from a mechanical point of view. In this case easy and accurate adjustment of the coupling is no longer possible. Moreover, mechanical vibrations or the like involve considerable variations of the adjusted coupling.

The present invention avoids these drawbacks whilst conserving the above-mentioned advantages and consists in that the movable coil is arranged in the region of the strongest curvature of the lines of force of the magnetic field produced by the stationary coil and is movable substantially in the direction of the lines of force there available.

The movable coil is preferably arranged so that 40 with the loosest coupling the axis of the coil extends substantially perpendicularly to the lines of force produced by the stationary coil. Furthermore the axes of the two coils preferably extend 45 parallel with each other. If the axis of the movable coil extends normally to the lines of force the modification of the coupling obtained by a given displacement is a maximum.

If the coil system is surrounded by metal screening 50 means the movable coil, according to a further feature of the invention, is arranged so that the coupling decreases when the coil approaches the neighboring wall of the housing.

The invention will be more clearly understood 55 by reference to the accompanying drawing.

Figure 1 represents diagrammatically a stationary and a movable coil.

Figure 2 is a graph of the value of the coupling factor of the two coils in accordance with the 5 displacement of the movable coil.

In Figure 1 the reference 1 designates a stationary coil and 2 a movable coil each of which is provided with an iron core 3 and 4 respectively. The coils are screened by a metal housing. For 10 the sake of clearness the mechanical attachment of the coils, which is not important for the present invention, has not been represented.

The lines of force of the magnetic field produced by the stationary coil are indicated by 15 dotted lines 5. The movable coil 2 is located in the region of the strongest curvature of these lines of force and its axis extends almost perpendicularly to the lines of force available at this point. The coil 2 is movable in the direction of the lines 20 of force there available, as is indicated by arrows 6 and 7. In the illustrated position of the movable coil the coil-centre is at 8. At this point the lines of force have an upwardly direct component which induces a definite voltage on the coil 2. If, on the contrary, the coil is located at 10 the 25 lines of force embraced by the coil have a component which is directed downwardly in the figure and by which a voltage is induced on the coil, which, if desired, has the same value but is oppositely directed. It will be appreciated that between the points 8 and 10 there is a point 9 at 30 which no voltage is induced on the coil 2, i. e., consequently that the two coils are then magnetically decoupled. In the case of magnetic decoupling the axis of the movable coil 2 will extend substantially perpendicularly to the lines of 35 force set up in the coil.

In Figure 2 the square of the coupling factor (K^2) has been plotted in accordance with the displacement (d) of the movable coil 2 for the arrangement shown in Figure 1. The point from which the co-ordinates originate has been chosen in accordance with the point 9 in Figure 1. The displacement (d in mms.) in the direction 6 on the abscissa-axis has been plotted on the right-hand 40 side and the displacement in the opposite direction 7 on the left-hand side. The degree of the coupling factor was chosen at will and plotted according to a logarithmic scale. Generally a comparatively small portion A, corresponding to 45 a displacement a , of the obtainable adjusting range will be utilized. As appears from Figure 2 an equally strong coupling can be obtained on either side of the point 9 at which the two coils are decoupled magnetically. If there are no metal 50 55

screening means for the coils, the coil 2 may be located on one or on the other side of the point 9. If, however, metal screening means are provided it is advantageous to locate the coil 2 at 8 since in this case the coil is as remote as possible from the neighbouring wall of the housing; in this manner the neighbouring wall of the housing only slightly affects the natural inductivity of the coil 2 in case of a displacement. As appears from Figures 1 and 2 the coupling decreases if the movable coil approaches the wall of the housing.

What I claim is:

- 15 1. In a high frequency band-pass filter, a stationary and a movable coil arranged with their axes in spaced parallel relation, there being one position of adjustment of the movable coil such that it is located in the region of the greatest curvature of the lines of force of the magnetic field produced by the stationary coil whereby the coils are substantially in decoupled relation, the movable coil being adapted for lateral adjustment in either direction from its first-mentioned position for varying the degree of coupling between said coils.
- 20 2. In a high frequency band-pass filter, a stationary and a movable coil arranged one above the other and with their axes in spaced parallel relation, a conductive shield surrounding said

coils, there being one position of adjustment of the movable coil such that it is located in the region of greatest curvature of the lines of force of the magnetic field produced by the stationary coil whereby the coils are substantially in decoupled relation, the movable coil being adapted for lateral adjustment in either direction from its first-mentioned position for varying the degree of coupling between said coils, and for equal adjustments of the movable coil the degree of coupling being less in the direction towards the adjacent side of the shield than in the opposite direction. 5

3. A high-frequency coupling device including a stationary and a movable inductor each having a 15 coil and a magnetic core, a conductive shield surrounding said inductors, said inductors being positioned on either side of the shield axis with their axes parallel to each other and to the axis of said shield, and means for adjusting the movable inductor transversely of the axis of said shield whereby the coupling between said inductors may be adjusted, the arrangement being such that with adjustment of the movable inductor toward the shield wall, the coupling first decreases to a minimum and then increases but at a different rate of change. 20 25

EWOUW ADRIAAN VAN YZEREN.
